UNITED STATES PATENT OFFICE.

SAMUEL JAMES HALLIDAY, OF WATERVLIET, NEW YORK, ASSIGNOR, BY MESNE ASSIGNMENTS, TO CLUETT, PEABODY & CO., INC., OF TROY, NEW YORK, A CORPORATION OF NEW YORK.

TAB-INSERTING MECHANISM.

1,117,564.

Specification of Letters Patent. Patented Nov. 17, 1914.

Application filed November 30, 1912. Serial No. 734,384.

To all whom it may concern:

Be it known that I, SAMUEL J. HALLIDAY, a citizen of the United States, residing at Watervliet, county of Albany, and State 5 of New York, have invented certain new and useful Improvements in Tab-Inserting Mechanism, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a top plan view of a portion of a sewing-machine provided with my improved mechanism, whereby it is adapted for inserting collar-tabs, the needle and presser-foot bar being shown in horizontal section and one end of the collar and tab being shown in the proper inserting 20 position determined by the gage-mechanism. Fig. 2 is a similar view with the collar, presser-foot and needle removed. Fig. 3 is a view in perspective of the gage for the tab. Fig. 4 is a view in perspective 25 of the gage for the wing-end of the collar-body. Fig. 5 is a plan view of one end of the collar with its inserted tab. Fig. 6 is a vertical cross-section of the presser-foot taken on the broken line 6-6 in Fig. 1. Fig. 7 is a vertical cross-section taken 30 through the throat-plate on the broken line 7-7 in Fig. 2.

This invention relates more particularly to mechanism for inserting buttonhole-tabs 40 in the end-portions of wing-collars, such as is shown in Fig. 5.

The principal object of the invention is to facilitate the insertion of the tab, and to secure uniformity and accuracy in the 45 location of the tab in the finished collar. In a collar of this type the body-portion of the collar is formed of two blanks or members having their edges inturned by means of folding-machines in the usual manner, 50 said blanks being superimposed one upon another with the inturned edges therebetween and secured together by through-and-through stitching along said inturned edges. The buttonhole-tab, which is first 55 formed and stitched, and which is prefer-

ably made of machine-turned blanks, is inserted between the body-members along an oblique end-portion thereof which is left unstitched until the tab is inserted, after which the collar is stitched through and 60 through along said oblique end-portion to complete the edge-stitching of the body of the collar and at the same time to secure the tab thereto.

In carrying out my invention I provide 65 gage-mechanism for placing in their proper relative positions the end of the collar body and the tab at the beginning of the inserting operation, and means for separately guiding the inturned edge of the upper 70 body-member and the inturned edge of the lower body-member along said oblique end-portion during the inserting operation.

Referring to the drawings wherein the invention is shown in preferred form, 1 represents the bed of a sewing-machine which is shown provided with a throat-plate, 2, work-feeding mechanism, 3, presser-foot, 4, and needle, 5, forming part of the stitch-forming mechanism, other parts of which 80 are located beneath the throat-plate through an aperture in which the needle plays. The stitch-forming mechanism and work-feeding mechanism may be of any type adapted for stitching collars and cuffs. 85

A gage, 6, for the wing-end, 13, of the collar-body is mounted upon the bed by means of a set-screw, 7, in position to form a guide for locating the end of the collar-body so that its oblique end-portion, 8, will 90 extend parallel with the direction of feed-movement and in proper relation to the needle, 5. In this position it will be apparent that the gage, 6, projects partly across the path of feed-movement of the collar-body. To enable the collar-body to ride freely over the gage, 6, in response to the operation of the feed-mechanism, I form the gage, 6, with a beveled edge, 9, presented to the work, of such reduced thickness or attenuation as to readily permit the work to ride thereover. In like manner a gage, 10, for the tab is mounted upon the bed by means of a set-screw, 11, in position to form a guide for locating the tab, 12, in proper 100 relation to the body of the collar for the beginning of the inserting operation. This gage, 10, extends partly across the path of feed-movement of the tab, 12, and I have shown it formed with a beveled edge, 14, 105 110

presented to the work, which edge is so reduced in thickness or attenuated as to permit the tab to ride thereover in response to the feed-movement of the collar body.

- 5 The presser-foot is formed with a depending edge-flange, 15, adapted to engage the inturned edge of the upper member, 16, of the collar-body along the oblique end-portion, 8, and guide said edge during the inserting operation. I also provide an undercut gage, 17, directly in front of the presser-foot adapted to enter between the members of the collar body and to engage the inturned edge of the lower member, 18, thereof, directly beneath the inserted portion of the tab, and to guide said edge along said oblique end-portion, 8, during the inserting operation.

The several gages, 6, 10, and 17, may be mounted upon the bed in any known manner, and the shape of the gages, 6 and 10, may be changed for different styles of collar.

What I claim as new and desire to secure by Letters Patent is—

- 25 1. In a machine for inserting collar-tabs, and in combination, stitch-forming mechanism; feed-mechanism; a presser-foot; and gage-mechanism for the end of a collar-body and end of a tab, respectively, having 70 gage-members projecting across the path of feed-movement of the collar and having beveled edges presented to the work over which the work is adapted to ride.

2. In a machine for inserting collar-tabs, and in combination, stitch-forming mechanism; a presser-foot; work-feeding mechanism; a gage for the end of the collar-body extending partly across the path of feed-movement of the collar-body; and a gage 80 for the end of the tab projecting partly across the path of feed-movement of the tab, the portions of said gages in the path of feed-movement of the work having beveled edges presented to the work.

- 45 3. In a machine for inserting collar-tabs,

and in combination, stitch-forming mechanism; work-feeding mechanism; a presser-foot; an undercut gage directly in front of the presser-foot adapted to enter between the members of the collar-body and guide 50 the infolded edge of the lower member of said body underlying the inserted portion of the tab; and gage-mechanism for the end of a collar-body and end of a tab, respectively, having gage-members projecting across the 55 path of feed-movement of the collar and having beveled edges presented to the work over which the work is adapted to ride.

4. In a machine for inserting collar-tabs, and in combination, stitch-forming mechanism; work-feeding mechanism; a presser-foot having a depending flange adapted to engage and guide the inturned edge of the upper member of the collar-body above the tab; an undercut gage directly in front of 65 the presser-foot adapted to enter between the members of the collar-top and to engage the inturned edge of the lower of said members beneath said tab; and gage-mechanism for the end of a collar-body and end of 70 a tab, respectively, having gage-members projecting across the path of feed-movement of the collar and having beveled edges presented to the work over which the work is adapted to ride.

5. In a sewing-machine, and in combination, stitch-forming mechanism; work-feeding mechanism; a presser-foot; and a locating-gage for the work, having a member projecting transversely of the path of the 80 work in rear of the presser-foot, said gage-member having a beveled edge presented to the work over which edge the work is adapted to ride.

In testimony whereof, I have hereunto set 85 my hand this 22nd day of November, 1912.

SAMUEL JAMES HALLIDAY.
